REMOTE CONTROL FOR A TOY VEHICLE

Felix Gilbert, New York, N.Y., assignor to De Lux Reading Corporation, a corporation of New Jersey

Filed Mar. 31, 1966, Ser. No. 1,707

Term of patent 7 years

(Cl. D34—15)

FIG. 1

FIG. 2

FIG. 3

FIG. 4

FIG. 5

FIG. 6

FIG. 1 is a perspective view of a remote control for a toy vehicle, showing my new design;

FIG. 2 is a front view;

FIG. 3 is a plan view;

FIG. 4 is a side view thereof;

FIG. 5 is a rear view;

FIG. 6 is a bottom view.

I claim:

The ornamental design for a remote control for a toy vehicle, substantially as shown.
